METHOD AND APPARATUS FOR SHEATHING CORES

Sidney E. Borgeson, Rome, N. Y., assignor to General Cable Corporation, New York, N. Y., a corporation of New Jersey

Application July 27, 1932, Serial No. 625,174

22 Claims. (Cl. 117—40)

This invention relates to a method and apparatus for providing a core with a fibrous jacket, and more particularly a seamless felted jacket of intimately interentangled fibers. It is an object of the invention to provide an improved method of applying a felted fibrous jacket to a core. It also is an object of the invention to provide an apparatus for carrying out the improved method. Other objects and advantages of the invention will appear hereinafter.

It will be apparent from the following description that the new method and apparatus may be used for coating various types of cores, both flexible and rigid, solid and hollow, and having varying cross sections. Merely for convenience the invention will be described with reference particularly to the insulation of electrical conductors. An illustrative embodiment of the invention selected merely for descriptive purposes is shown in the accompanying drawings, in which:

Fig. 1 is a top plan view of a machine for applying a felted insulating covering to electrical conductors;

Fig. 2 is an end elevation of the machine shown in Fig. 1, from the right-hand side of Fig. 1;

Fig. 3 is an end elevation of the machine from the left-hand side of Fig. 1;

Fig. 4 is a view substantially on the line 4—4 of Fig. 2;

Fig. 5 is an enlarged vertical section substantially on the line 5—5 of Fig. 4;

Fig. 6 is a view of the applicator for applying fibers to an electrical conductor, substantially on the line 6—6 of Fig. 5;

Fig. 7 is an elevation of the separating roll for tearing apart the fibers of a fleecy strand and for throwing the separated fibers on to the applicator;

Fig. 8 is an elevation of the feeding roll for feeding the fleecy strand to the separating roll;

Fig. 9 is a longitudinal section through another type of feeding roll; and

Fig. 10 is a partial section to enlarged scale substantially on the line 10—10 of Fig. 9.

Various methods have been proposed heretofore for applying a fleecy strand of fibrous material to an electrical conductor to form an insulating jacket. Many of the methods of the prior art have not proven practical, either because the method of forming the jacket produces an insulating wall having distinct seams which open up when the conductor is bent, or because of the difficulty and cost of especially preparing

the fibrous material in a form suitable for application to the conductor with available apparatus.

This invention provides a method and apparatus for forming a compact, seamless felted jacket about a core, which jacket comprises fibers variously and indiscriminately arranged and so interentangled and compacted as to form a unitary fabric wall. The individual fibers comprising the jacket do not themselves extend in any one general direction, but extend in any and all directions so as to be completely interentangled and uniformly felted. The jacket may be made extremely thin, or it may be built up uniformly to any practical thickness.

This description refers to the forming of a 15 felted jacket on an electrical conductor. It will be understood, of course, that there is no limitation, actual or implied, to forming the jacket immediately overlying the conductor itself. The 20 felted jacket may be formed directly on the conductor, or it may be formed over another covering or coverings on the conductor. The fibers may be of any suitable material such, for example, as cotton, asbestos, flax, silk or other material. If desired, separate superimposed 25 layers of the same or different materials and thicknesses may be formed on the conductor, and these layers may or may not, as desired, be separated by intervening protective or coating materials. Sheathed cores and electrical conductors produced by the method and apparatus claimed herein are claimed in my copending 30 divisional application Serial No. 128,250, filed February 27, 1937.

Referring particularly to Figs. 1 to 4 of the drawings, it will be seen that the housing 11 containing the greater part of the mechanism is for convenience mounted upon an angle-bar frame 12 supported upon standards 13.

As may best be seen in Fig. 2, a drive shaft and pulley, (not shown) driven by any suitable source of power are connected by means of a belt indicated at 14 which passes from the driving pulley upwardly and over a pulley 15, downwardly and under a pulley 16, again upwardly and over a pulley 17, and then downwardly to the driving pulley. For reasons which will appear hereinafter, the driving connection is such that during operation the pulleys 15 and 17 are rotated at a very 50 high speed, while the pulley 16 desirably is rotated at a lower speed.

The pulley 16 conveniently is utilized through the medium of a variable, speed-reduction driving connection to drive a feeding roll for feeding 55

a fleecy strand of fibers from a supply into the machine at a regular predetermined rate. As is best shown in Fig. 4, in the illustrative embodiment the pulley 16 is rigidly secured on one end of a horizontal shaft 18 passing through and rotatably mounted in the lower portion of the housing 11. Referring now to Figs. 3 and 4, secured on the other end of the shaft 18 is a worm 19 meshing with a worm wheel 20 secured on the lower end of a vertical shaft 21 which is rotatably mounted in a bracket 22 projecting from the housing 11.

On the vertical shaft 21 is a roller 23 which is keyed to the shaft so as to rotate therewith but which is free to move longitudinally along the shaft. The periphery of the roller 23 frictionally engages the face of a disk 24 secured on one end of a horizontal shaft 25 passing through and rotatably mounted in the housing 11. The disk 24 is resiliently pressed against the roller 23, as by means of a spiral spring 26 surrounding the shaft within the housing 11. Also bearing against the face of the disk 24 is a roller 27 mounted on a vertical shaft 28 aligned with and spaced slightly from the end of the shaft 21. The shaft 28 is rotatably mounted in a bracket 29 projecting from the housing 11. The roller 27 is keyed to the shaft 28 so as to rotate therewith, but is free to move longitudinally along the shaft. It will be apparent that the shaft 21 acts through the medium of the roller 23 to turn the disk 24, and that rotation of the disk 24 causes the roller 27 and the shaft 28 to turn.

Means are provided for simultaneously sliding the rollers 23 and 27 on the shafts 21 and 28 so as to vary inversely the distances of the rollers from the center of the disk 24, thereby permitting a wide range of variation in the relative speeds of the two shafts. Conveniently, such means comprises a block 30 having recesses 31 and 32 for receiving the wheels 23 and 27, the block 30 being mounted to slide vertically on a guide 33 mounted in the brackets 22 and 29.

Vertical adjustment of the block 30 may be made by means of the vertical screw 34 rotatably mounted in the brackets 22 and 29, and having screw-threaded engagement with a vertical opening through the block. Conveniently the screw 34 projects upwardly beyond the bracket 29 and is provided with a control wheel 35. It will be apparent that by turning the wheel 35 the block 30 may be raised or lowered so as to move the rollers 23 and 27 over the face of the disk 24 toward and away from the center of the disk, thereby varying the speed of the shaft 28 relative to the speed of the shaft 21.

Desirably the variable speed friction clutch arrangement just described is enclosed within a protecting casing 72 secured on the end of the housing 11. In the drawings the casing 72 is shown broken away in order to disclose the mechanism within.

The upper end of the vertical shaft 28 projects above the bracket 29 and has secured on its end a worm 36 meshing with a worm wheel 37 which is rigidly secured on one end of a shaft 38 passing through and rotatably mounted in the upper part of the housing 11.

As may best be seen in Figs. 5 and 8, secured on the shaft 38 within the casing 11 is a toothed feeding roll 39. The feeding roll 39, which normally rotates at a relatively slow speed, feeds a supply of fibrous material into the machine.

Conveniently the fibrous material is supplied in lap form wound into a roll 40. The roll 40 may

be supported on a center rod 41 having on its ends grooved rollers 42. The rollers 42 rest on the upwardly inclined guides 43 projecting rearwardly from points on the housing 11 slightly below the shaft 38. It will be apparent that the weight of the roll of fibrous material 40 will be sufficient to keep the supply of material pressed against the feeding roll 39 at all times, and it will also be apparent that as the feeding roll 39 rotates it will remove the lap from the supply roll and feed the fibrous material into the machine. It may be desirable to provide the guides 43 with guard members 44 to aid in keeping the supply roll 40 in alignment.

As is best shown in Fig. 5, the cover 45 over the feed roll preferably is pressed resiliently toward the feed roll so as to insure uniform feeding of the fibrous material in the machine, as well as to hold the strand while the separating roll teeth tear the fibers of the strand apart. In the illustrative embodiment the cover 45 is provided with a handle 46, and has a limited freedom of movement toward and away from the feed roll along the guide pins 47. Spiral springs 48 surrounding the pins 47 normally press the cover 45 toward the feed roll, such movement being limited by engagement of the handle 46 with the housing 11 to prevent actual contact between the cover 45 and the feed roll 39.

In place of the feeding roll shown in Figs. 5 and 8 it may be desirable in some cases to use a feeding roll having fine axial slots along its surface instead of teeth. Such a roll 39a is illustrated in Figs. 9 and 10, and merely by way of example the axial slots 39b may be $\frac{1}{32}$ inch wide, 35 $\frac{1}{64}$ inch deep and spaced $\frac{1}{64}$ inch apart.

Referring particularly to Fig. 5, it will be seen that the fleecy strand of fibrous material picked up by the feeding roll 39 from the supply roll 40 is fed into a chamber 54 which contains the separating roll 49. The separating roll is rotatably mounted in the housing 11 parallel to the feeding roll 39, and upon one end of the roll axle extending beyond the housing 11 is secured the pulley 55. During operation of the machine the separating roll is rotated at high speed, and the pins 50, projecting radially from the surface of the separating roll, tear apart the individual fibers of the fleecy strand and project the separated fibers at high speed into the applicator 52 chamber 52.

In order to attain substantially complete separation of the individual fibers comprising the fleecy strand the pins 50 preferably are numerous and somewhat widely spaced, and uniformly distributed over the roll, axially so that the paths of no two pins exactly coincide, and circumferentially so that the separated fibers will form a practically continuous stream. The number of pins will depend upon the degree of separation of the fibers desired. A suitable arrangement comprises placing the pins in multiple spiral paths, as shown in Fig. 7, and desirably each pin is flattened at the tip to an edge parallel to the direction of motion. Since the separating roll 49 rotates very rapidly, and the feeding roll 39 rotates at a relatively low speed, the pins 50 will completely tear apart the fibers of the fleecy strand, and the separated fibers will be thrown off from the separating roll by centrifugal force 70 into the applicator chamber 52.

As the separated fibers are thrown off from the separating roll 49 they are projected at high speed into the chamber 52. Mounted in the chamber 52 is an applicator 53 which collects the 75

separated fibers and applies them in a multiplicity of overlying thin layers on the core 51 as the core moves linearly through the chamber. The applicator 53, as shown more fully in Figs. 4 and 6, is rotatably mounted in the chamber 52, with both of its ends extending beyond the housing 11. Secured on one end of the applicator is the driving pulley 17, and during operation of the machine the applicator is rotated at high speed.

The applicator has an axial opening through which the core 51 passes, from right to left in Fig. 1. If desired, the core 51 may be coated with an adhesive, as by dipping it in a bath 55 of adhesive compound, before it enters the applicator. The core is drawn through the applicator by means of a suitable take-up device 63.

As is more clearly shown in Fig. 6, the ends of the applicator desirably are provided with removable guide members 56 and 57, conveniently held in place by means of the nuts 58 and 59 screwthreadedly engaging and clamping the longitudinally split ends 60 and 61 of the applicator. These guide members are replaceable by other members having different bores to permit the machine being used most advantageously for cores of different diameters and for fibrous jackets of different thicknesses. Desirably, sealing means indicated at 62 protect the bearings of the applicator against abrasion from the fibers in the chamber 52.

Within the chamber 52 the applicator has one or more offset sections, there being three in the illustrative embodiment, which give to it a crank shape. Desirably these offset sections are designed so as to counterbalance each other. Each of the offset sections is provided with a flat surface 65 for collecting the separated fibers in the chamber 52, and desirably with means such as a series of closely spaced, curved, spring wire teeth 66 for conveying the collected fibers to the core and for pressing the fibers on to the core. The rapidly rotating applicator 53 collects the fibers on the surface 65 in the form of a loosely matted ribbon, the fibers so collected extending in any and all directions. As the applicator rotates, this thin ribbon of fibers is drawn toward and wrapped around the core, and since the applicator rotates at a very high speed, the fibers will be applied to the core as it passes through the applicator in a multiplicity of overlying thin layers.

The spring teeth 66 press the thin ribbon of fibers on to the core as it is applied, and this compacting of the variously and indiscriminately arranged fibers produces in the composite a felted fabric jacket about the core which has substantially uniform characteristics throughout its thickness.

In order to permit access to the separating roll and the applicator, the chambers 52 and 54 in the housing 11 desirably are closed by a cover 68 hinged to the housing at 69. For convenience, a handle 18 is provided, and spring clips 71 serve to keep the cover closed during operation.

The operation of the machine as a whole will now be summarized. The wire or other core 51 which is to be coated with fibrous material is moved linearly through the axial opening in the applicator. Conveniently, the wire is drawn through the machine by means of a power driven take-up device. The speed at which the wire is moved through the machine will depend upon the width of the machine, the speed at which the

applicator rotates, and the thickness of the fibrous jacket which is to be applied. If desired, the wire may be coated with an adhesive just before it enters the machine.

The feeding roll 34, the separating roll 49 and the applicator 53 all are rotated. The feeding roll is turning slowly, its driving connection including speed reduction mechanism, and also including means for accurately varying the speed of the feeding roll. The speed of the feeding roll will depend on the thickness and composition of the fleecy strand of fibrous material being fed into the machine, the speed of the other moving elements of the machine, and the thickness of the fibrous jacket which is to be applied to the wire. It has been found that for insulating magnet wire in a machine as described the speed of the feeding roll desirably is variable over a range of from one turn per eighty feet of conductor to one turn per eight feet of conductor.

The fleecy strand of fibers, for example asbestos, desirably is supplied to the machine in lap form. In a machine of the type specifically disclosed and used for insulating magnet wire the lap may be 5 1/4 inches wide, running 200 grains to the yard, and put up in a package 18 inches in diameter. Such a package will weigh approximately 10 pounds and will cover about 50,000 feet of No. 18 magnet wire.

The feeding roll conveys the fibrous strand from the supply package to the separating roll. The separating roll is set with pins desirably one-quarter of an inch long or longer, and the separating roll is rotating at high speed. Desirably, the speed of the separating roll will be such as to separate completely the individual fibers of the strand. Experimental data thus far obtained indicate that the speed in revolutions per minute should be at least

$$\frac{10,000}{\sqrt{D}}$$

20

25

30

35

40

45

50

55

60

65

where D is the diameter of the roll in inches. The pins of the separating roll tear the fibers of the fleecy strand apart, and the fibers are thrown off from the separating roll by centrifugal force into the applicator chamber.

The high speed of the separating roll is necessary not only to tear the fibers apart, but also to insure that the separated fibers will be thrown off from the roll. If a few fibers should cling to the teeth, no harm will be done, for these fibers will be carried around and thrown off into the applicator chamber upon the next turn of the separating roll.

Within the applicator chamber, the applicator is turning at high speed, desirably as high as is practical for the structural strength of the applicator, for example about 6,000 revolutions per minute or more. Desirably this speed will be such as to give a pitch or angle of lay between the fibers and the conductor axis of about 65 degrees. The quality of the fibrous covering applied to the conductor is about proportional to the angle of lay between the fibers and the conductor.

The separated fibers which are thrown from the separating roll into the applicator chamber collect on the forward face of the applicator to form a thin, very loosely matted ribbon. The fibers so collected are variously and indiscriminately arranged, and extend in any and all directions. This ribbon is not a true fabric, but there is sufficient cohesion between the fibers as they are pressed together by the rotating applicator

70

75

so that as the applicator rotates the thin ribbon is wrapped around the conductor.

The applicator teeth, conveniently of curved spring wire and closely spaced, lay the ribbon of fibers on the conductor and press the ribbon into place. Thus it will be seen that a fibrous wall is built up of a wide, spirally-wrapped, thin ribbon of fibers, the wall having a multiplicity of layers, and the spiral wrapping having a pitch which is 10 very small compared to the width of the ribbon. The ribbon is continuously pressed on to the conductor as it is applied, and the wall which is formed becomes a unitary, seamless felted covering in which the identity of the individual 15 layers is lost.

It will be noted that the applicator partially obstructs the flow of fibers into the applicator chamber for a brief interval during each rotation. It has been found that this does not in 20 any way interfere with the operation of the applicator in building up a unitary felted fibrous wall. The applicator is so designed that it tends to scoop up any fibers which may collect on the inner wall of the applicator chamber so that 25 these fibers become a part of the ribbon being fed to the conductor. It will be noted also that as the applicator moves past the opening between the separating and applicator chambers, the separating roll will remove from the outer surface 30 of the applicator any body of fibers which may have accumulated thereon.

This invention provides a method and apparatus for applying to cores of various sizes and shapes a unitary, seamless jacket of felted fibers. 35 The method and apparatus permit the application of an extremely thin jacket, or, if desired, the jacket may be built up to any practical thickness. In either case, the character of the jacket is the same, notably a unitary felted covering 40 having substantially uniform characteristics throughout its thickness.

The foregoing description of certain specific embodiments of the invention is illustrative merely, and is not intended as defining the limits 45 of the invention.

I claim:

1. The method of forming a compact felted jacket of intimately interentangled fibers about a core which comprises moving the core lineally, 50 continuously projecting a thin stream of disconnected fibers toward the moving core in a direction essentially normal to the core, and applying the fibers of the stream to the core in a multiplicity of overlying thin layers.

55 2. The method of forming a compact felted jacket of intimately interentangled fibers about a core which comprises moving the core lineally, continuously projecting a thin stream of disconnected fibers toward the moving core in a direction 60 essentially normal to the core, applying the fibers of the stream to the core in a multiplicity of overlying thin layers, and individually pressing each layer of fibers on the core to form in the composite a unitary seamless jacket having substantially uniform characteristics 65 throughout its thickness.

3. The method of forming a compact felted jacket of intimately interentangled fibers about 70 a core which comprises moving the core lineally, advancing a fleecy strand of fibers toward the moving core, disintegrating the fleecy strand, projecting the disconnected fibers toward the moving core in a continuous thin stream in a 75 direction essentially normal to the core, and ap-

plying the fibers of the stream to the core in a multiplicity of overlying thin layers.

4. The method of forming a compact felted jacket of intimately interentangled fibers about a core which comprises moving the core lineally, 5 advancing a fleecy strand of fibers toward the moving core, disintegrating the fleecy strand, projecting the disconnected fibers toward the moving core in a continuous thin stream in a direction essentially normal to the core, applying 10 the fibers of the stream to the core in a multiplicity of overlying thin layers, and compacting each layer of fibers as it is applied to the core to form in the composite a unitary seamless jacket of felted and interentangled fibers in which the 15 layers cannot be individually identified.

5. The method of forming a compact felted jacket of intimately interentangled fibers about a core which comprises moving the core lineally, 20 continuously projecting a thin stream of disconnected fibers toward the moving core in a direction essentially normal to the core, collecting the fibers adjacent the core in the form of thin loosely matted ribbon, and wrapping the ribbon around the core in a multiplicity of overlying 25 layers.

6. The method of forming a compact felted jacket of intimately interentangled fibers about a core which comprises moving the core lineally, 30 continuously projecting a thin stream of disconnected fibers toward the moving core in a direction essentially normal to the core, collecting the fibers adjacent the core in the form of thin loosely matted sections of ribbon, cutting the ribbon into short sections, wrapping the ribbon around 35 the core in a multiplicity of overlying thin layers, and individually pressing each layer of fibers on the core to form in the composite a unitary seamless jacket having substantially uniform 40 characteristics throughout its thickness.

7. The method of forming a compact felted jacket of intimately interentangled fibers about a core which comprises tearing apart the fibers of a fleecy strand, continuously projecting a thin stream of the disconnected fibers toward the 45 core in a direction essentially normal to the core, and applying the fibers of the stream to the core in a multiplicity of overlying thin layers.

8. In apparatus for applying a fibrous jacket to a core, the combination of means for moving 50 a core lineally, means for feeding a fleecy strand of fibers toward the moving core, means for tearing the fibers of the strand apart and for throwing them at high speed toward the moving core in a direction essentially normal to the core, 55 and means for collecting the mutually unsupported fibers adjacent the core in a thin loosely matted ribbon and for wrapping the ribbon about the moving core.

9. In apparatus for applying a fibrous jacket 60 to a core, the combination of means for moving a core lineally, means for feeding a fleecy strand of fibers toward the moving core, means for tearing the fibers of the strand apart and for throwing them at high speed toward the moving core 65 in a direction essentially normal to the core, means for collecting the mutually unsupported fibers in a thin loosely matted ribbon and for wrapping the ribbon about the moving core, and means for compacting the fibers into a unitary 70 felted jacket enclosing the moving core.

10. In apparatus for applying a fibrous jacket to a core, the combination of means for moving a core lineally, means for applying a coating of adhesive to the core, means for feeding a fleecy 75

strand of fibers toward the moving core, means for tearing the fibers of the strand apart and for throwing them at high speed toward the moving core in a direction essentially normal to the core, 5 and means for collecting the mutually unsupported fibers in a thin loosely matted ribbon and for wrapping the ribbon about the moving core.

11. In apparatus for applying a fibrous jacket to a core, the combination of means for moving 10 a core lineally, means for feeding a fleecy strand of fibers toward the moving core, means for tearing the fibers of the strand apart and for throwing them at high speed toward the moving core in a direction essentially normal to the core, 15 and means for collecting the mutually unsupported fibers and applying them in a multiplicity of overlying thin layers on the core.

12. In apparatus for applying a fibrous jacket to a core, the combination of means for moving 20 a core lineally, means for feeding a fleecy strand of fibers toward the moving core, means for tearing the fibers of the strand apart and for throwing them at high speed toward the moving core in a direction essentially normal to the core, 25 means for collecting the mutually unsupported fibers and applying them in a multiplicity of overlying thin layers on the moving core, and means for compacting the fibers as they are applied into a unitary seamless jacket enclosing the 30 moving core.

13. In apparatus for applying a fibrous jacket to a core, means for separating the fibers of a fleecy strand and for throwing the separated fibers toward a core in a direction essentially 35 normal to the core, and means for collecting the mutually unsupported fibers and applying them in a multiplicity of overlying thin layers on the core.

14. In apparatus for applying a fibrous jacket 40 to a core, means for applying separated fibers to a core to form a unitary seamless felted jacket, which means comprises a stationary casing, a rotatable member mounted within said casing and having an axial opening for passage of a 45 core, means for projecting separated fibers into said casing in a direction essentially normal to the core passage, and an eccentric section on said rotatable member for collecting separated fibers in the form of a thin loosely matted ribbon and 50 for wrapping the ribbon about the core in a multiplicity of overlying layers.

15. In apparatus for applying a fibrous jacket to a core, means for applying separated fibers to a core to form a unitary seamless felted jacket, 55 which means comprises a stationary casing, a rotatable member mounted within said casing and having an axial opening for passage of a core, means for projecting separated fibers into said casing in a direction essentially normal to the core passage, an eccentric section on said 60 rotatable member for collecting separated fibers

in the form of a thin loosely matted ribbon and for wrapping the ribbon about the core in a multiplicity of overlying layers, and means on said rotatable member for pressing the ribbon on the core as it is applied thereto to compact 5 the fibers into a unitary seamless jacket.

16. In an apparatus for applying a fibrous covering to a core, means for conveying separated fibers in a thin stream to the core, a stationary housing surrounding the core for collecting the 10 fibers, and rotatable means within the housing for wrapping the fibers about the core.

17. In an apparatus for applying a fibrous covering to a core, a stationary chamber partly surrounding the core for collecting fibers, means for 15 conveying separated fibers into the chamber, and means within the collecting chamber for wrapping the fibers about the core.

18. In an apparatus for applying a fibrous covering to a core, a stationary chamber having 20 openings for the linear passage of a core through the chamber and an opening parallel to the core axis for admitting fibers, means for conveying separated fibers into the chamber, and means within the chamber for wrapping the fibers 25 about the core.

19. In an apparatus for applying a fibrous covering to a core, a stationary collecting chamber about the core, rotatable means mounted within the collecting chamber coaxially with the core 30 and extending substantially the entire length of the chamber for wrapping fibers about the core, and means for conveying fibers into the chamber.

20. In an apparatus for applying a fibrous covering to a core, means for wrapping the fibers 35 about the core comprising a bearing section enclosing the core, an eccentric applying section disposed beside and rotative about the core, said applying section including means resiliently engaging the core, and means for conveying fibers 40 to the applying means.

21. In an apparatus for applying a fibrous covering to a core, means for moving a fleecy strand of fibers toward the core, means for separating the fibers of the strand and for conveying the 45 separated fibers in a thin stream toward the core, a housing surrounding the core for collecting the fibers, and rotatable means within the housing for repeatedly cutting across the stream of fibers and for applying the fibers to the core in a multiplicity of overlying layers. 50

22. In an apparatus for applying a fibrous covering to a core, means for conveying separated fibers in a thin stream toward the core, a stationary housing surrounding the core for collecting the fibers, and rotatable means within the housing for picking up the mutually unsupported fibers in the form of a thin ribbon and wrapping the ribbon around the core in overlying layers. 55

SIDNEY E. BORGESON. 60
